LOUIS BINDER, OF NEWARK, NEW JERSEY.

BOX AND METHOD OF MAKING THE SAME.

1,417,295.

Specification of Letters Patent. Patented May 23, 1922.

Application filed May 18, 1920. Serial No. 382,212.

To all whom it may concern:

Be it known that I, LOUIS BINDER, a citizen of the United States, and a resident of Newark, county of Essex, and State of New Jersey, have invented certain new and useful Improvements in Boxes and Methods of Making the Same, of which the following is a specification.

This invention relates to an improved box adapted for use as a box for cigars and like articles, the box being made of thick cardboard and so assembled as to make it cheap to make and also strong enough to thoroughly withstand ordinary usage so as to prevent any danger to the contents.

The invention relates to a box of the kind described in which the structure of the box is such as to prevent inward movement of the front and back, which are the longer vertical walls, and also inward movement of the top and bottom of the box, so that the box is capable, as a cardboard box, of withstanding excessive pressure, especially when the contents, such as cigars, are pressed into the box by pressure applied to the outside of the box so that the lid is forced to a closed position.

The invention further consists in the method of making the box so as to provide a box capable of being used in the manner described.

The invention is illustrated in the accompanying drawing, in which Figure 1 is a perspective view of a box made according to my invention with the lid opened. Figure 2 is a face view of the blank from which the body of the box is made. Figure 3 is a cross-section of the box blank with its sides bent up. Figure 4 is a similar view showing the bottom as pushed into the box a slight distance. Figure 5 is a detail perspective on line 5—5 in Figure 4. Figure 6 is a top view of the corner of the part of the box shown in Figure 5, and Figure 7 is a cross-section of the box similar to Figure 4, but illustrating the lid in place and a paper covering secured to the outside of the box proper.

The body of the box is preferably made of one piece, and the blank is shown in Figure 2 having the central portion 10, which forms the bottom of the box, and wings extending therefrom, one of the wings 11, when bent up, forming the rear side of the box, the part 12 forming the front wall or side of the box, and the wings 13 and 14 forming the ends of the box.

I use very stiff cardboard which does not bend without opening up a gap on the outer edge of the fold, this cardboard being approximately one-eighth of an inch thick, and when folded, the gaps or openings 15 shown in Figure 3 are formed. To avoid the necessity of filling these corners, and making the box not only stronger, but more economical, I apply pressure to the bottom, usually all over the surface, but at least along all of its edges, to force the bottom up between the sides 11 and 12, and preferably in far enough so that the bottom face of the box is substantially flush with the bottom edges of the sides.

When bent, the cardboard does not break, but the bent portions are connected by a strip 16 which, when the bottom is pressed upward, is folded in, as at 17 in Figure 4, this permitting no breaks at the joints and being adapted to make a tight box, so that there is no chance of evaporation or drying up of the contents.

The two ends 13 and 14 are folded up and rest against the ends of the sides 11 and 12, but I prefer to make these ends as long as the distance between the top of the walls 11 and 12 and the top face of the bottom when it is in its inset or retracted position, these end walls then being pressed inward, as shown in Figures 5 and 6, the connecting web or strip 16 being folded in as shown at 18 in Figure 5, the ends of these end walls, as 19, fitting against the inner faces of the sides 11 and 12.

When the box is thus conformed, the parts are preferably covered with a paper cover 20, usually pasted both on the inside and outside of the box, and, being secured to the box by adhesive, holds the parts against outward movement and the sides of the box do not spread. The paper can be suitably ornamented, in the case of cigar boxes being usually printed as an imitation of wood.

The cover 21 is made so as to extend at least to the edges of the vertical walls of the box proper and to rest thereon, and is provided with a sheet 22 on its inner face, the sheet 22 fitting snugly within the vertical walls of the box, the lid being usually held by a suitable hinge 23 of the ordinary type, which in practice is made by pasting a strip of strong fabric to both the box and the lid.

Boxes of this kind are well adapted for use as cigar boxes, because on account of

100

110

the high cost and the rarity of cedar a box of this kind is desirable as to its cost, but must be made to withstand the same strains as a wooden box.

5 When the cigars are put into a box they are of such bulk as to prevent the closing of the lid to a point beyond about half way toward a closed position. The lids are then usually pressed down by hand until they are 10 nearly shut, and then many boxes are assembled and pressed into a press and subjected to pressure to force the lids shut tight. The pressure necessary to bring this about is great, and an ordinary cardboard box 15 collapses under such pressure. I have, however, with this improved form of box, made of one-eighth inch stock, subjected a single box to a pressure of over 2200 pounds without any damage to the box whatever. This 20 is due to the fact that heavy cardboard resists longitudinal pressure, and the pressure on the lid is taken up by the walls 11 and 12 and 13 and 14 endwise. Inward pressure on the long sides, that is, the front 25 and back 11 and 12, is resisted successfully because for their entire lengths these sides bear at the top against the sheet 22 of the lid, and at the bottom bear against the front and back edges of the bottom 10 of the box 30 proper. The bottom is held against inward movement as it rests against the edges of the sides 13 and 14.

The lid is also provided, in the preferred form of box, with a marginal flange 21^a, 35 which, when the lid is closed, extends down around the outside of the ends and of the front side of the box, thus providing a space or a groove between the sheet 22 and the flange 21^a, this groove receiving the top 40 edges of the ends and front side of the box proper.

Cardboard boxes used as cigar boxes heretofore have been unsuccessful because pressure on the front and back walls 11 and 12 45 is not successfully resisted and a slight bulge in these walls destroys the cigars as the pressure on the ends of the cigars causes them to crack.

In my present form of box, due to the 50 reasons heretofore enumerated, all the walls successfully withstand any tendency to press

them inward and the joints of the box proper are tight and the cigars in the box do not dry out. Another advantage of this form of lid is that when the boxes have been 55 forced shut by the excessive pressure, the lid is fastened down, in the case of a wooden box, by a small tack at the center.

I may employ similar means, but I prefer to provide a fastening in the form of a clasp 60 24 which snaps onto a button on the top face of the lid, but irrespective of the fastening means used, the corners of a wooden box, that is, the corners of the front, are very often, when released from the pressure, 65 pushed up by the cigars so that at the corners of the box, at the front, there are openings made, by reason of this warping of the lid, which permit the escape of moisture from the box and the cigars become brittle and 70 very often lose their flavor.

In my improved box, even if such slight warping takes place, the liability of the box being even partly opened is removed, because the lids never bend sufficiently to let any 75 part of the front edge of the sheet 22 ride above the top edge of the front wall 12.

It will be understood that the box can be made of different forms and of different sizes without departing from the scope of 80 my invention.

I claim:

1. A box made of thick cardboard and having its bottom, sides and ends formed of one piece, the bottom being inset between the 85 sides, and the ends being inset between the sides and resting on the bottom.

2. A box made of thick cardboard and having its bottom, sides and ends formed of one piece, the bottom being inset between 90 the sides, and the ends being inset between the sides and resting on the bottom, and a lid to cover the top edges of the sides and ends and having a projecting sheet to fit between the sides, whereby the sheet and the 95 bottom brace the sides against inward movement, and whereby the ends brace the lid and bottom against inward movement.

In testimony that I claim the foregoing, I have hereto set my hand, this 13th day of 100 May, 1920.

LOUIS BINDER.
